[57] **CLAIM**

The ornamental design for a combined bracket and convection oven bowl, as shown and described.

DESCRIPTION

FIG. 1 is a perspective view from the front-left-top side of a combined bracket and convection oven bowl showing my design;

FIG. 2 is a front elevational view thereof, the rear side being a mirror image;

FIG. 3 is a left side elevational view thereof, the right side being a mirror image;

FIG. 4 is a top plan view thereof;

FIG. 5 is a bottom plan view thereof; and,

FIG. 6 is a front elevational view thereof with an additional lid shown in broken line retained vertically by the bracket. The broken line showing of the lid is for illustrative purposes only and forms no part of the claimed design.

FIG. 1

FIG. 4

FIG. 2

FIG. 5

FIG. 3

FIG. 6
